UNITED STATES PATENT OFFICE.

JOSEPH WADSWORTH, OF PATERSON, NEW JERSEY.

SWIVEL-LOOM.

SPECIFICATION forming part of Letters Patent No. 740,717, dated October 6, 1903.

Application filed February 2, 1903. Serial No. 141,480. (No model.)

To all whom it may concern:

Be it known that I, JOSEPH WADSWORTH, a citizen of the United States, residing at Paterson, in the county of Passaic and State 5 of New Jersey, have invented certain new and useful Improvements in Swivel-Looms, of which the following is a specification, reference being had therein to the accompanying drawings.

- 10 My invention relates to swivel-looms; and it consists in a swivel-shuttle rail carrying a plurality of racks and pinions and superposed banks of compound swivel-shuttles operated by said racks and pinions, each bank of shuttles independently operative; in means for 15 operating the various banks of swivel-shuttles simultaneously, alternately, or at any interval desired; in the peculiar construction and arrangement of the said swivel shuttles and 20 the individual supports therefor; in means for changing the position of the swivel-shuttle rail in either direction at alternate intervals or intermittently in either direction, and in various combinations of the above devices 25 and other known parts of the weaving mechanism of a swivel-loom, as will be hereinafter more specifically set forth in the claims.

The main object of my invention is to provide in a swivel-loom a mechanism adapted 30 to weave figures comprising various colors at any predetermined position in the fabric being woven or to weave figures some of one color and some of another color, if so desired, and at any predetermined point without stopping the loom, the whole mechanism to be automatic in its operation and to be controlled by the jacquard.

In the drawings similar letters of reference indicate like parts throughout the various 35 figures of the drawings.

Figure 1 shows my compound swivel-shuttle rail, partly front and partly back view. Fig. 2 shows partly a top and partly a bottom view of my rail. Fig. 3 is a section through 40 my rail on the lines $x-x$ in Fig. 1. Fig. 4 is an end view of my rail. Fig. 5 is a front view of the back part e of the bottom compound swivel-shuttle. Fig. 6 is a plan view of a complete bottom compound swivel-shuttle. Fig. 7 is a side view of the bottom swivel-shuttle. Fig. 8 is a front view of a swivel-

loom embodying my invention. Fig. 9 is a plan view of Fig. 8. Fig. 10 is a left-side elevation of Figs. 8 and 9. Fig. 11 is a plan view of my swivel-shuttle rail on line y in Fig. 8. Fig. 12 is a plan view of my swivel-shuttle rail on line z in Fig. 8. Fig. 13 is a detail perspective view showing the construction of operative connection of swivel-shuttle-rack-moving device for one set of swivel-shuttles on one side of loom. The same device is used for the second row of shuttles on the other side of loom. Fig. 14 is a view showing the connections and moving device for my shuttle-racks from jacquard to jack and 65 two vibrators.

My compound swivel-shuttle rail, as shown in Figs. 1 and 2, consists of two longitudinal parts—a front part A and a back part A' —which are secured together by suitable means, 70 as by screws a^3 .

An arm A^2 , secured to the swivel-shuttle rail, connects it with rod L , which is preferably square and has the rounded portion, as indicated by the reference-letter l , at the end 75 of which is secured the downwardly-extending arm l^7 , having a sleeve l^6 , that may be secured at the point desired on the round portion l of the rod L .

The arm l^7 passes through an opening a^8 80 in the outer end of the arm A^2 .

The swivel-shuttle rail carries the sliding racks B and B' , the former in part A , the latter in part A' , and studs b and b' , secured to said racks, extend upwardly through longitudinal vertical slots a and a' , in which slots 85 said studs are reciprocated to operate said racks. The swivel-shuttle rail is hung on studs a^9 , secured to the plate a^{10} , which is in turn connected to the mechanism for raising 90 and lowering the rail, and said studs a^9 project through the longitudinal horizontal slots a^2 , which permit the whole swivel-shuttle rail to be moved laterally, sliding on said studs a^9 to change field of operations of the top 95 swivel-shuttles E , which is operated by the rack B through the pinions c , and of the lower swivel-shuttles E' , operated by the rack B' through the pinions C' .

The L-shaped supports D and D' of the upper and lower shuttles, the blocks C and C' , and the pinions c and c' are supported on and 100

secured together by the studs or screws c^2 . The plates or supports D are also secured to the rail by screws d.

The space between A and A' has a filling 5 d' . A plate a^4 , having a threaded opening, is secured to the back part A' by screw a^5 , through which the securing-screw a^3 is passed.

The rod L is mounted to slide in the brackets l' and l^2 , which are secured to the top rail 10 f^3 of the loom-frame F. To the rod L is secured the rack I^8 . The rod L and the swivel-shuttle rail A A', to which it is operatively connected, are caused to move either to the right or to the left by the shifting device K— 15 a device fully described in former applications filed by me and which are now pending in the United States Patent Office.

The device K comprises a ratchet-wheel and a pinion k' , secured to a stud, levers loosely 20 mounted on and depending one on each side of said stud, each lever having a pawl adapted to engage said ratchet-wheel and turn it and the pinion in one direction and the other pawl to turn it in the opposite direction, stops to 25 limit the movement of said levers, and means throwing the respective pawls into or out of engagement with the said ratchet. The levers are operated from the jacquard through the connecting-cords k , and as the jacquard may 30 lift either lever once or oftener, successively and at intervals, and the intermediate pinion k^2 meshing with both the pinion k' and the rack I^8 the swivel-shuttle rail A A' can be shifted frequently in one direction at intervals, as desired, to permit the swivel-shuttles 35 to weave figures where required in the fabric being woven.

Brackets a^7 are secured to swivel-shuttle rail and have arms a^6 secured to braces g^8 , 40 having openings g^4 g^4 , through which the shafts G G' are permitted to slide on the right and left of the loom, respectively.

Lever-arms g and g' are suitably mounted 45 on the shafts G and G' and are pivotally connected by pins g^2 with the pitmen b^2 and b^3 , the other ends of said pitmen being pivotally secured to the studs b and b' of the racks B and B'.

On the picking-stick holders f are secured 50 studs g^8 . Pivoted to said studs g^8 are brackets g^6 , pivotally secured at g^7 to shafts G G' below the collars g^5 .

On the lower ends of the shafts G G' are the levers g^9 . Pitmen g^{10} and g^{11} connect, 55 respectively, levers g^9 with brackets g^{12} and g^9 with bracket g^{13} . (See Figs. 8 and 13 of drawings.)

The bracket g^{13} is secured to rod i^{11} and the bracket g^{13} to the rod i^{13} , which rods are held 60 by the supports f' and f^2 .

In the bracket H, which is secured to the side of the loom-frame, are mounted the short shafts h and h' , h having secured thereto the levers i and i' , and h' the levers i^2 and i^3 .

Knuckle-joints i^4 and i^5 join the levers i^3 65 with the connecting-rod i^7 , and said connect-

ing-rod i^6 and i^7 are suitably attached to the two vibrators i^8 and i^9 of a head-motion, which are operated from the jacquard, as shown in Fig. 14.

70

The levers i^{10} are an element in the picking-stick-operating mechanism, and in this case it is not deemed necessary to go into details concerning that.

The rod i^{11} is pivotally connected with the 75 lever i^2 by the pin i^{12} and the rod i^{13} with lever i by the pin i^{14} .

The vibrators i^8 and i^9 are operated by a jack M, of the usual or any well-known construction, to which they are operatively connected by the cords i^{15} and by levers m' and m^2 , fulcrumed in a bracket m^3 , which may be secured to or near the jacquard. Said levers m' and m^2 are held normally in a horizontal position by the springs m^5 , the spring-ends of the 80 levers being connected by the cords m to the jack M, and the opposite ends of the levers are connected to the jacquard by the cords m^4 .

The construction shown and described 85 accomplishes five things—viz., the weaving automatically of the figures in the fabric where desired; the changing and mixing automatically of colors in the figures without interfering with or stopping the operation of the loom; the shifting of the swivel-shuttle rail

carrying a plurality or series of independently-operative sets of swivel-shuttles containing threads of several colors by means actuated by the jacquard; the operating of the independent sets of swivel-shuttles indirectly by 90 the jacquard upon the downward movement of the jacquard mechanism instead of operating said swivel-shuttles by the upward movement of the jacquard mechanism, and obviates the necessity for using a complex 95 head-motion having chains, &c.

The ordinary way of operating a swivel-loom is by having one ground-card between 100 each swivel-pick, and the reason for this arose from the fact that the swivel mechanism on a swivel-loom lies dormant until it is called. This calling takes place in the following manner:

As the figure approaches which it is intended to swivel the last ground-card previous to the swivel is cut in such a manner 105 that certain hooks are raised up in the jacquard-machine, releasing the mechanism of the swivel and allowing it to operate. This operation can be continued indefinitely, but always with a ground-card intervening between the swivel-picks, and this ground-card was apparently hitherto a necessity which could not be disposed of. By my invention, 110 however, I dispense with the intervening ground-card between the swivel-picks.

The advantage of this invention comes in 115 when it is desired to make a two-colored swivel effect without any intervening ground-pick. Given the double-tier swivel-batten and in the regular way of swiveling, we have first one

120 tier, then a ground or blank card, and then the second tier. By means of my levers and

125

130

135

140

145

150

springs or other equivalents this invention does away with the ground-cards between the swivel-picks, which ground-cards are indispensable in the regular swivel-loom. One of the principal objects of this invention is to do away with these intervening ground-cards between the swivel-picks, and this is accomplished by obtaining an upward-and-downward motion to one revolution of the jacquard-machine by means of my levers and springs. As the machine rises one of the swivel tiers commences to work, and as the jacquard-machine comes down the springs work the jacks, so that the second tier of the swivel-batten is operated without any intervening blank card; and this could not be accomplished except by means of my levers and springs or other equivalent means capable of performing the same function. The rising jacquard mechanism, as is readily perceived, can perform the function of pulling up; but it cannot push down nor pull up when it is going down; but with my invention I secure a direct upward pull when the jacquard mechanism is rising and indirectly a rising pull when the jacquard mechanism is descending. The negative motion of the jacquard-machine is virtually converted into a positive motion, the spring acting when the machine is going out of action.

Figs. 15 and 16 will serve to illustrate the advantages of my invention.

In Fig. 15 is shown one ground-pick between each swivel-pick, the colors of the swivel-shuttle thread alternating and having a ground-pick between them. In Fig. 15, *s* is a red swivel-pick, *g* the ground-pick, and *s'* the blue swivel-pick, *g* another ground-pick, *s* another red swivel-pick, *g* another ground-pick, *s'* another blue swivel-pick, &c.

In Fig. 16 is shown one ground-pick, then two swivel-picks, then a ground-pick, then two more swivel-picks, or between every two ground-picks two swivel-picks of the same or different colors.

In Fig. 16, *s* and *s'*, two swivel-picks of different colors, are shown between every two ground-picks *g*, *s* being a red swivel-pick, and *s'* a black swivel-pick.

As is obvious, colors and combinations may be varied *ad libitum*.

The mechanical devices shown in the drawings for indirectly communicating a positive action from the jacquard, or what may be termed the "converting of a negative into a positive action," although practical and effective is not only mechanical contrivance, possibly, that might be made to perform the principal function of my invention, which I desire to claim broadly without limiting myself to the specific construction shown. To change the patterns on the ordinary swivel-loom entails considerable expense, while with my loom I merely have the expense of cutting my cards. It is obvious that while not necessary on a loom having a single bank of shuttles my double-acting jacquard may never

theless be used to great advantage. The loom shown in the drawings has two banks of swivel-shuttles, and either or both simultaneously may be shot through the swivel-shed, according to the pattern; by the operation of the jacquard-machine, and the shuttles may have the silk supplied thereto of the color or colors desired, so that the color or colors desired in the figure are supplied automatically as called for by the pattern.

It is obvious that any alternation of colors desired may be produced, as either the upper or lower bank of shuttles may be at rest or in operation whenever required. The parts are assembled as indicated in the various figures. The swivel-shuttle rail is operated as above described.

The upper and lower bank of shuttles are operated as follows: The jacquard through the cords *m*⁴ tilts the levers *m'* and *m''*, and the springs *m*⁵ cause them to return to their horizontal position and cause the jack *M* by the cords *i*¹⁵ to work the vibrators *i*⁹ and *i*⁹, which being operatively connected by the shafts *i*⁶ and *i*⁷ and levers *i*, *i'*, *i''*, and *i'''* with the rods *i*¹¹ and *i*¹⁸ cause said rods to reciprocate or slide and turn the shafts *G* and *G'*, and the shafts *G* and *G'* are connected with and operate the pitmen *b*² and *b*³, which are attached to the rack-studs *b* and *b'* to move rack *B*, which drives the front or upper shuttles *E*, and the rack *B'*, which drives the back or lower shuttles *E'*.

The peculiar construction and arrangement of my compound swivel-shuttles, as shown, is a necessary element of my invention to constitute an efficient and practical swivel-loom, because I may require both the upper and lower swivel-shuttles to carry the swivel-weft of different colors through the swivel-shed at the same time or not and because it is necessary to supply weft when the bobbins in the swivel-shuttles need replenishing. My back or lower shuttle *E'* is therefore a compound swivel-shuttle made in two parts *e* and *e'*. Pins *e*² and *e*³ are secured to the part *e* and are provided with slots *e*⁴. The part *e'* is provided with holes *e*⁵, into which the pins *e*² and *e*³ enter and are held by the pressure of the springs *e*⁶, which are secured to the part *e*. The said springs when pressed by the insertion of the pins *e*² and *e*³ enter slots *e*⁷ in the sides of the openings *e*⁶, locking the parts *e* and *e'* together, as shown in Figs. 6 and 7. The part *e* is L-shaped and has the rack portion *e*⁹, as shown in Figs. 6 and 7. A rubber band *e*¹⁰, provided with an eye *e*¹¹, is used for tension purposes. When necessary to place a bobbin of weft in the shuttle *E'*, which is overlapped by the shuttle *E*, the part *e'* of the shuttle *E'* is easily removed and replaced.

With this description of my invention, what I claim, and desire to secure by Letters Patent, is—

1. In a swivel-loom, a compound swivel-shuttle rail, in combination with banks of separable superposed swivel-shuttles carried

thereby and means for independently operating said banks of shuttles, substantially as set forth.

2. In a swivel-loom, the combination with a compound swivel-shuttle rail, of an upper and lower bank of swivel-shuttles, supports for said swivel-shuttles on which the shuttles may be reciprocated independently of one another, and sets of racks and pinions operating independently of each other mounted in said swivel-shuttle rail to operate respectively the upper and lower swivel-shuttle, substantially as set forth.

3. In a swivel-loom, the combination with a compound swivel-shuttle rail, of an upper and lower bank of swivel-shuttles, supports for said swivel-shuttles on which the shuttles may be reciprocated independently of one another, and sets of racks and pinions operating independently of each other mounted in said swivel-shuttle rail to operate respectively the upper and lower shuttle, and means, operatively connected with the jacquard, for driving or reciprocating said racks and pinions, substantially as set forth.

4. The swivel-shuttle rail, an upper and a lower bank of swivel-shuttles, one above the other, carried by said rail, supports with slanting sides for said swivel-shuttles secured to said swivel-shuttle rail, a rack and pinions mounted to drive the upper bank of swivel-shuttles and a rack and pinions mounted to drive the lower bank of swivel-shuttles, the lower shuttles comprising two separable portions, in combination with an actuating mechanism operated from the jacquard to move said swivel-shuttle rail laterally in either direction, substantially as set forth.

5. The swivel-shuttle rail, an upper and a lower bank of swivel-shuttles one above the other carried by said rail, supports with slanting sides for said swivel-shuttles secured to said swivel-shuttle rail, a rack and pinions mounted to drive the upper bank of swivel-shuttles and a rack and pinions mounted to drive the lower bank of swivel-shuttles, the lower shuttles comprising two separable portions, in combination with an actuating mechanism operated from the jacquard to operate the upper bank of swivel-shuttles, and a like actuating mechanism also operated from the jacquard to drive the lower bank of swivel-shuttles, substantially as set forth.

6. The swivel-shuttle rail, an upper and a lower bank of swivel-shuttles, one above the other, carried by said rail, supports with slanting sides for said swivel-shuttles secured to said swivel-shuttle rail, a rack and pinions mounted to drive the upper bank of swivel-shuttles, and a rack and pinions mounted to drive the lower bank of swivel-shuttles, the lower shuttles comprising two separable portions, in combination with an actuating mechanism operated from the jacquard to move said swivel-shuttle rail laterally in either direction, an actuating mechanism driven from

the jacquard to operate the upper bank of swivel-shuttles, and a like actuating mechanism also operated from the jacquard to drive the lower bank of swivel-shuttles, substantially as set forth.

7. In a swivel-loom, a compound swivel-shuttle rail, carrying banks of swivel-shuttles and racks and pinions for independently operating the same in combination with a jacquard-machine, and means for operatively connecting said racks with the rise-and-fall mechanism of a jacquard-machine to operate the racks upon the downward movement of the jacquard mechanism, substantially as set forth.

8. In a swivel-loom, a swivel-shuttle jack, in combination with the rise-and-fall mechanism of a jacquard-machine, and operative connections between the two whereby the jack is indirectly operated by the jacquard upon the downward movement of the jacquard mechanism, substantially as set forth.

9. In a swivel-loom, a compound swivel-shuttle rail, in combination with independently-operating superposed banks of compound swivel-shuttles, means for actuating said shuttles and an actuating mechanism, operated from the jacquard, to progressively move said swivel-shuttle rail laterally in either direction, substantially as set forth.

10. In a swivel-loom, a swivel-shuttle jack, in combination with the rise-and-fall mechanism of a jacquard-machine, and operative connections between the two whereby the jack is operated upon the downward movement of said mechanism, substantially as set forth.

11. In a swivel-loom, swivel-shuttles, in combination with the rise-and-fall mechanism of a jacquard-machine, and operative connections between the two whereby the shuttles are operated upon the downward movement of said mechanism, substantially as set forth.

12. In a swivel-loom, swivel-shuttles, and a rack and pinions for operating the same, in combination with the jacquard-machine, and operative connections between the rack and pinions and the jacquard mechanism to drive the swivel-shuttles upon the downward movement of the same, substantially as set forth.

13. In a swivel-loom, the combination with the jacquard-machine and sets of swivel-shuttles, of means operatively connected with the jacquard mechanism to operate some of said shuttles simultaneously with the upward movement of said mechanism, and means operatively connected with the jacquard mechanism to operate some of said shuttles simultaneously with the downward movement of said mechanism.

14. In a swivel-loom, independently-operating banks of swivel-shuttles, adapted to operate simultaneously or successively and means for operating either, or both, of said banks of shuttles, as stated, between two ground-picks.

15. In a loom, the combination with a jacquard-machine of a jack device comprising a cam-wheel and shaft, a ratchet-wheel, fast on the shaft of the cam-wheel, a lever loose on the shaft of the cam-wheel, a pawl carried by said lever and adapted to engage with and operate said ratchet, and means operatively connecting said lever to the jacquard, to operate the lever and turn the cam-wheel upon

the downward movement of the jacquard **10** mechanism.

In testimony whereof I affix my signature in presence of two witnesses.

JOSEPH WADSWORTH.
